AUTOMATED BIMINI TOP DEVICE

CROSS-REFERENCE TO RELATED APPLICATION

This application is a continuation-in-part of provisional patent application Ser. No. 61/195,103 filed Oct. 3, 2008 for Automated Bimini Top Device.

BACKGROUND OF THE INVENTION

The present invention relates to convertible top covers for boats, commonly called bimini tops, and more particularly to an improved automated bimini top device having a movable framework specially adapted and powered to move between an extended and retracted position in a free-standing unit that is readily mounted upon a boat deck or radar arch without any additional supporting framework or binding straps.

In recreational boating, the so-called "bimini top" is a convertible cover erected upon the deck of the boat and made to be deployed at an elevation comfortably above the heads of the passengers. Drawing its name from the Bimini islands in the Bahamas where it was first employed by boaters to provide desired shade from the strong rays of the tropical sun, the standard type of bimini top and those convertible boat covers of the same nature generally comprise a flexible canvas material secured to a foldable support frame that is erected across the deck and pivotally attached thereto. These standard types of foldable bimini tops can be raised when needed or lowered into a substantially flat position upon the deck when not in use or when an overhead obstruction may otherwise require its lowering. Deployment of these foldable bimini tops is often done manually but has been designed to be power driven, such as those described in U.S. Pat. No. 6,209,477 to Briedenweg and U.S. Pat. No. 6,983,716 to Ankney et al.

While prior art systems for automatic retractable bimini tops have been satisfactory in their operation, their movable support frames with pivotal rods and struts have been somewhat complicated in construction and have not afforded easy mounted attachment to the boat deck or other rigid structure such as radar arches typically found on recreational boats of today. In view of the recognized harm cause by extended exposure to the sun and in appreciation of the benefits of providing sun protection for those onboard recreational boats, it warrants having a convertible bimini top on a recreational boat whenever possible, and providing an associated structure that is automated and easy to attach to existing boats is of significant value and importance for the protection of passengers and crew on board boats against excessive sun exposure and the evident risks of skin cancer caused thereby.

SUMMARY OF THE INVENTION

Accordingly, it is a general purpose and object of the present invention to provide an improved retractable bimini top for recreational boats that is fully automated and capable of easy mounted attachment to the deck of the boat or other rigid supporting structure thereon.

A more particular object of the present invention is to provide an improved automated bimini top device capable of deployment in a free-standing unit that is readily mounted upon a boat deck or radar arch without any additional supporting framework or binding straps.

Another object of the present invention is to provide an automated bimini top device for recreational boats that is capable of providing effective sunshade protection to persons

2

on board the boat without presenting obstructions to their movement or performance of tasks on or around the deck.

Still another object of the present invention is to provide an improved automated bimini top device that is particularly suitable for retrofitting existing recreational boats with needed means for shade protection of those on board.

A further object of the present invention is to provide an automated bimini top device that is capable of hands free operation and supplying shade protection quickly and reliably whenever required.

10 A still further object of the present invention is to provide an automated bimini top device that is relatively inexpensive to manufacture, easy to assemble and ready to install upon existing boat structure.

Briefly, these and other objects of the present invention are 15 accomplished by an automated bimini top device comprising a foldable frame assembly adapted to carry a flexible canvas material thereon and powered to move the canvas selectively between a retracted position and an extended position. The frame assembly includes a rear bow member supported in a 20 fixed raised position, a front bow member adapted to slide along a length of the rear bow and pivot relative thereto, and a middle bow member pivotally connected along the length of the front bow and adapted to move in an opposite rotational direction thereto. Actuator means assembled to the rear bow member are operatively connected to move the front bow member in reversible directions outward and away from the rear bow into the extended position and inward and toward the rear bow into the retracted position. The middle bow member is coupled to a guide strap connected between the rear and front bow members and further attached beneath the canvas material to maintain contact with the canvas during retraction and provide central support thereof in the extended position.

25 For a better understanding of these and other aspects of the present invention, reference should be made to the following detailed description taken in conjunction with the accompanying drawings in which like reference numerals and character 30 designate like parts throughout the figures thereof.

BRIEF DESCRIPTION OF THE DRAWINGS

40 For a fuller understanding of the nature and objects of the present invention, references in the detailed description set forth below shall be made to the accompanying drawings in which:

45 FIG. 1 is a perspective side view of the automated bimini top device of the present invention shown with its canvas top in its fully deployed state;

50 FIG. 2 is a further perspective side view of the automated bimini top device of FIG. 1 with the canvas top appearing in phantom to show the underlying frame assembly in its extended state;

55 FIG. 3 is an upper side perspective view of the top portion of the fully extended frame assembly of the present automated bimini top device shown in FIG. 2;

FIG. 4 is a lower side perspective view of the bottom portion of the fully extended frame assembly of the present automated bimini top device shown in FIG. 2;

FIG. 5 is a side perspective view of the top portion of the frame assembly of the present automated bimini top device between its extended and retracted state; and

60 FIG. 6 is a side perspective view of the underlying frame assembly of the present automated bimini top device in its fully retracted state.

DESCRIPTION OF THE INVENTION

The following serves to describe a preferred embodiment of the present invention and the best presently contemplated

mode of its production and practice. This description is further made for the purpose of illustrating the general principles of the invention but should not be taken in a limiting sense, the scope of the invention being best determined by reference to any associated claims.

Referring to the drawings, the following is a list of structural elements of the present automated bimini top device, generally designated **10**, and those associated elements shown employed in connection with the present invention:

- 10** automated bimini top device;
- 11** fold-away frame assembly;
- 12** canvas material;
- 13** mounting plate;
- 14** rear bow member;
- 16** rear support struts;
- 18** guide tracks;
- 20** front bow member;
- 22** hinge slides;
- 24** hydraulic actuators;
- 25** actuator drive arms;
- 26** front support struts;
- 28** middle bow member;
- 30** jaw slides;
- 32** jaw slide stops;
- 34** guide strap support;
- 34a** guide strap line;
- 34b** guide strap loop;
- 35** take-up roller;
- 36** torsion spring;
- B boat;
- P hydraulic pump; and
- L hydraulic lines.

The present automated bimini top device **10** comprises a fold-away frame assembly **11** that is adapted to support a flexible canvas material **12** thereon and powered to move the canvas material automatically between a retracted position, as seen in FIG. 6, and an extended, fully deployed position, as seen in FIG. 1. Use of hydraulic power is preferred to move the frame assembly **11** in its intended fashion and would be provided by conventional hydraulic pump **P** (shown in phantom outline) mounted and installed upon the boat structure. Alternatively, pneumatic or electrical power may be used. A mounting plate **13** shown in FIG. 1 formed in a U-shaped configuration may be used to couple the present device **10** and its fold-away frame assembly **11** to the boat structure **B** providing an integral attachment surface for mounting the device **10** across the deck of the boat. Mounting of the present bimini top device **10** may alternatively be made by separate plates secured on either side of the deck or directly to the boat structure on each side.

Referring now to FIGS. 2 through 5, the working framework of the fold-away frame assembly **11** is made from a strong, durable and corrosion-resistant material, such as stainless steel or aluminum alloy, and includes a rear bow **14** raised and supported upon the mounting plate **13** with a pair of rear support struts **16** fixed in a substantially erect attitude upon the mounting plate and connected near the top of the side legs of the rear bow on either side to keep the frame assembly upright and free-standing in the sense it does not need to be affixed to any overhead structure. The rear bow **14**, as are those other working bow members of the frame assembly **11** described below, is a tubular member formed in a substantially U-shaped configuration having a crossbar extending between opposite side legs. Along the lower portion of each side leg of the rear bow **14**, a guide track **18** channel-like in form is disposed and adapted to engage a deck hinge slide **22** pivotally connected at the foot of each side leg

of a front bow **20** on either side thereof. In this connection, the hinge slide **22** may be moved through the guide track **18** in either direction and thereby move the front bow **20** with associated rotation in a direction that will either extend or

5 retract the frame assembly **11**. A front support strut **26** pivotally mounted on either side of the frame assembly **11** is extended upward and pivotally connected at the top thereof to an intermediate position along each side leg of the front bow **20** to allow for proper folding movement of the front bow.

10 A conventional hydraulic actuator **24** cylindrical in form is connected to the pump **P** via tubular lines **L** and is mounted along each side leg of the rear bow **14** in connection with the guide track **18** to generate movement of the hinge slides **22** along the guide track that drives the deployment of the frame assembly **11**, particularly the front bow **20**. The actuator drive arm **25**, typically a shaft-like member made to move outward and inward of the hydraulic actuator **24** in controlled strokes under hydraulic pressure, is coupled to the hinge slide **22** disposed within the guide track **18** on each side leg of the front bow **20**. When the hydraulic actuators **24** are activated, the drive arms **25** will move accordingly and push (for extending) or pull (for retracting) the bottom of the front bow **20** along the guide track **18** via hinge slides **22**. While the front bow **20** is being pushed from its bottom by the actuators **24**, the front

25 support struts **26** rotate to a substantially erect position to support the front bow when fully extended.

Referring more particularly to FIGS. 3 and 5, a middle cross bow member **28** is further included in the fold-away frame assembly **11** for supporting the canvas material **12** in its 30 extended position intermediate of the rear bow member **14** and front bow member **20** when fully deployed and to further prevent the extended canvas from sagging. The side legs of the middle cross bow member **28** are pivotally connected on each side to respective legs of the front bow member **20** using 35 jaw slides **30**. The jaw slides **30** are a traditional mounting device that allow a bow to swing or pivot in place 180 degrees. During deployment of the present fold-away frame assembly **11**, the middle cross bow member **28** is adapted to pivot upon the front bow member **20** via the jaw slides **30** and made to 40 swing a certain angle away from the front bow and toward the rear bow member **14** into a position wherein the top arm or crossbar of the middle cross bow is substantially at the same level as the crossbars of the rear bow and front bow members when fully deployed. A jaw slide stop **32** is stationed along 45 each side of the front bow **20** just rearward of the jaw slides **30** to engage the sides of the pivoting middle cross bow **28** and thereby stop the rearward pivotal movement of the middle cross bow at the desired angle. Alternatively, the jaw slides **30** may be fitted with a mechanical stop to limit the rotation of 50 the middle cross bow **28** therein.

A guide strap support **34** is secured between the respective crossbars of the rear bow **14** and front bow **20** and centrally positioned along each. The guide strap support **34** is formed having an extended line section **34a** that is connected between 55 the rear bow **14** and front bow **20** and a loop section **34b** that is routed centrally about the respective crossbars of the rear bow **14** and the middle cross bow **28**. The guide strap support **34** along its line section **34a** is fastened beneath the canvas material **12**, typically by sewing, and via the loop section **34b** 60 serves during deployment of the fold-away frame assembly **11** to pull the middle cross bow **28** in a guided fashion away from its folded position alongside of the front bow **20** and toward the rear bow **14** until the jaw slide stops **32** engage the sides of the middle cross bow stopping it in the desired intermediate position in the fully deployed position of the assembly 65 shown in FIG. 3. In retraction of the fold-away frame assembly **11**, the loop section **34b** of the guide strap support

34 serves to support the level of the middle cross bow 28 preventing it from swinging downward and allowing the middle cross bow to move forward and back onto the front bow 20 in the fully retracted position. A take-up roller 35 is mounted centrally along the crossbar of the front bow 20 and assembled in conjunction with an associated torsion spring 36 to roll up and collect the canvas material during retraction. Substantially similar to the arched roller assembly shown and described in U.S. Patent Publication No. 2009-0031942, the spring-loaded take-up roller 35 also acts to draw the guide strap line 34a and loop section 34b in tension during retraction of the frame assembly 11 further preventing the canvas material from sagging during the fold-up retraction of the frame assembly 11.

Therefore, it is apparent that the described invention provides an improved retractable bimini top for recreational boats that is fully automated and capable of easy mounted attachment to the deck of the boat or other rigid supporting structure thereon. More particularly, the disclosed inventive device provides an improved automated bimini top device capable of deployment in a free-standing unit that is readily mounted upon a boat deck or radar arch without any additional supporting framework or binding straps. In the described embodiment, the present automated bimini top device is capable of providing recreational boats with effective sunshade protection for persons on board without presenting obstacles to their movement or obstructions to their performance of tasks on or around the deck. The disclosed automated bimini top device is particularly suitable for retrofitting existing recreational boats with needed means for shade protection of those on board. In addition, the present inventive device is capable of hands free operation and supplying shade protection quickly and reliably whenever required. Furthermore, the disclosed automated bimini top device is relatively inexpensive to manufacture, easy to assemble and ready to install upon existing boat structure.

Obviously, other embodiments and modifications of the present invention will readily come to those of ordinary skill in the art having the benefit of the teachings presented in the foregoing description and drawings. Alternate embodiments of different shapes and sizes, as well as substitution of known materials or those materials which may be developed at a future time to perform the same function as the present described embodiment are therefore considered to be part of the present invention. Accordingly, it is understood that this invention is not limited to the particular embodiment described, but rather is intended to cover modifications within the spirit and scope of the present invention as expressed in the appended claims.

What is claimed:

1. An automated bimini top device for a boat structure, comprising:
a piece of canvas material;
a frame assembly erected upon the boat structure and operatively connected to support the canvas material thereon, said frame assembly being adapted to fold together in reversible directions between a retracted and an extended position with the canvas material supported thereon, said frame assembly including a first bow member supported in a fixed raised position, a second bow member adapted to slide along a length of the first bow

member and pivot relative thereto, and a third bow member pivotally connected along a length of the second bow member and adapted to rotate relative thereto; actuator means operatively connected to the first bow member for moving the second bow member in reversible directions along the length of the first bow member pivotally outward therefrom into the extended position and backward along the length pivotally inward toward the first bow member into the retracted position; and strap means connected between the first and second bow members and looped intermediately therebetween about the third bow member for rotating the third bow member in opposite directions during movement of the second bow member, said strap means being further attached beneath the canvas material to maintain the canvas material upon the frame assembly between the retracted and the extended positions thereof.

2. An automated bimini top device according to claim 1, wherein said frame assembly further comprises:

a pair of first struts erected upon the boat structure and connected to the first bow member on either side thereof to support the fixed raised position thereof; and

a pair of second struts pivotally mounted on either side of the frame assembly and pivotally connected along the second bow member to allow for proper folding movement thereof.

3. An automated bimini top device according to claim 1, wherein said frame assembly further comprises:

a guide track member disposed along each side of the first bow member; and

a deck hinge slide pivotally connected to each side of the second bow member and adapted to engage the guide track member on either side of the first bow member.

4. An automated bimini top device according to claim 3,

wherein said actuator means comprises:

a hydraulic actuator attached along the first bow member and operatively connected to move the deck hinge slide in reverse directions along the guide track member.

5. An automated bimini top device according to claim 1,

wherein said frame assembly further comprises:

a jaw slide attached along each side of the second bow member and pivotally connected to each side of the third bow member to allow the third bow member to swing in place 180 degrees relative to the second bow member; and

a jaw slide stop stationed along each side of the second bow member adjacent to the jaw slide to limit swing angle of the third bow member relative to the second bow member.

6. An automated bimini top device according to claim 1, wherein said strap means comprises:

a guide strap fastened to the canvas material along the length thereof, the guide strap being formed having a linear section extending between the first bow member and a loop section routed centrally about the first bow member and the third bow member to draw the third bow member in a guided fashion away from the second bow member and toward the first bow member during extension of said frame assembly.
